UNITED STATES PATENT OFFICE

KARL KROLZIG, OF BERLIN-OBERSCHONEWEIDE, GERMANY, ASSIGNOR TO LOCKE INSULATOR CORPORATION, OF BALTIMORE, MARYLAND, A CORPORATION OF MARYLAND

CLAMP FOR CONDUCTORS

Application filed March 16, 1925, Serial No. 15,915, and in Germany July 18, 1924.

The invention relates to clamps for securing electric overhead lines, especially high tension lines, or conductors, and has for its object to provide a two-part clamp which is simple in construction, inexpensive to manufacture and which is simple and easy to attach.

To these and other ends, the invention comprises the various elements and combinations of elements as herein set forth.

In the drawings in which a single form of clamp is illustrated:

Figure 1 is a side elevation of a clamp constructed in accordance with the invention showing a conductor positioned therein.

Figure 2 is a cross-section taken on line 2-2 of Figure 1.

Figures 3 and 4 are perspective views, one showing the manner of connecting and the other showing the clamp with the cable in place, the clamping means being omitted from both figures.

Carrying clamps heretofore used for securing conductors to supporting masts are difficult to mount, particularly when at great height. This difficulty arises from the fact that the carrying clamp must first be fastened to the conductor cable which is under heavy strain and when so located must then be hung onto a string or chain of insulators by means of a clapper pan provided on the connector or on the upper part of the clamp itself. Numerous expedients have been employed in this art to avoid the difficulties but so far as applicant is aware he is the first to provide a simple clamp which is capable of ready attachment to a string of insulators and which can be assembled with the conductor after being mounted upon the insulators, as will be hereinafter more fully pointed out.

Referring now to the drawings in detail, the clamp comprises two counter-part members 1 and 2, the upper portions of which are formed as a clapper pan 3 and are adapted to be connected after being assembled on the clapper by a ring 4 which is pushed down over the neck, the ring being secured against shifting by cotters or pins 5 or the like. The lower portion of each

part of the clamp is extended into a supporting groove 6 into which the cable or conductor is adapted to be received. Side-wise or relative shifting of the portions 1 and 2 of the clamp is prevented by the projections 7, the projection on each portion being adapted to enter a corresponding recess 8 in the other cap or portion. When the clamp members are assembled there is provided a recess 9 at each central portion 55 which is adapted to receive a two-part auxiliary clamp which comprises two pressure pieces 10 and 11 which are pressed together or held by a bolt and nut 12. The lower ends of the pieces 10 and 11 form cheeks 60 13 and 14 which are adapted to grasp the cable 15 therebetween. The pieces 10 and 11 are retained in position and held against displacement from the body of the clamp by claws 16 and 17, respectively, which are 65 adapted to enter the corresponding grooves 18 formed on the clamp portions 1 and 2. It will be observed that not only do the pieces 10 and 11 serve to maintain the cable against lateral shifting with reference to the clamp 70 by claws 16 and 17, respectively, which are 75 adapted to enter the corresponding grooves 18 formed on the clamp portions 1 and 2. It will be observed that not only do the pieces 10 and 11 serve to maintain the cable against lateral shifting with reference to the clamp 75 but also assist the ring 4 in maintaining the portions 1 and 2 of the clamp in assembled position.

The carrying clamp after being assembled with the clapper 19 of the lowermost string 80 of insulators, is rotated, as shown in Figure 3, so that the longitudinal axis of the groove 6 is disposed substantially at an angle of 90° to the cable or conductor. The cable is then raised until it is in the upper 85 extremity of the recess 9 and the clamp is then rotated back to normal position and in such direction that the grooves 6 will underlie the adjacent portions of the conductor whereupon the cable is dropped into the 90 grooves and the auxiliary clamping device is attached to firmly grasp the cable as well as to maintain the parts of the clamp in assembled position.

Having now described my invention, what I claim as new and desire to secure by Letters Patent, is:

1. In a device of the character described, the combination with a support, of a carrying clamp comprising a pair of members 100

- having ball and socket connection with said support, the members each being provided with a cable supporting portion, and means engaging a cable for interlockingly connecting said clamp thereto.
2. An article of manufacture comprising a pair of members having interfitting engaging portions and conductor supporting portions, and means for preventing the separation of said members, said means also serving to engage and interlockingly connect a cable thereto.
3. A suspension clamp comprising a pair of similarly constructed cable carrying members formed with complementary portions forming, when assembled, a socket for engaging supporting means, auxiliary clamping devices provided with extensions clampingly engaging the socket forming portions of the clamp for holding them in assembled relation and other extensions adapted for engaging a supported cable for rigidly holding the same in position, and means holding said auxiliary members together.
4. A suspension clamp comprising a pair of similarly constructed members adapted, when assembled, to form a clapper pan, said members being provided with cable supporting grooves beneath said pan, said members being adapted for assembly about an associated clapper and forming a recess therebetween into which a cable to be supported is introduced and connected to the clamp by rotating the same until the grooves underlie said cable, and cable locking means comprising a pair of auxiliary clamps, the upper ends of which engage the members of the clamp and hold the same in assembled relation and the lower ends of which engage the cable and lock the same in place.
5. A suspension clamp comprising counterpart members mutually engaging and forming a socket for the reception of a headed support and each formed with spaced grooves adapted to receive and support a cable, and an auxiliary locking device located between said grooved portions and including relatively movable members, the upper ends of which grip the members of the clamp and firmly hold the same in assembled relation and the lower ends of which simultaneously grip the supported cable.
6. A suspension clamp comprising counterpart members having complementary portions defining, when assembled, a socket adapted for swivelled engagement upon a headed support, said members being formed with spaced grooved portions opening out at the top and adapted to receive and support a cable, auxiliary clamping members located between said grooved portions and having claw portions engaging said complementary members and having other portions
- adapted to engage a cable, and means extending transversely through said auxiliary clamping members for maintaining them in clamping engagement upon the cable and said complementary members for holding the latter assembled.
7. A suspension clamp comprising counterpart members having complementary portions defining, when assembled, a socket adapted for swivelled engagement upon a headed support, said members being formed with spaced grooved portions opening out at the top and adapted to receive and support a cable, auxiliary clamping members located between said grooved portions and having claw portions engaging said complementary members and having other portions adapted to engage a cable, means extending transversely through said auxiliary clamping members for maintaining them in clamping engagement upon the cable and said complementary members for holding the latter assembled, and a band slidably engageable upon said complementary members for preventing separation thereof.
8. A suspension clamp comprising a pair of socketed members adapted for rotatable engagement upon a headed support and formed with saddle portions engageable beneath a conductor to support the same, said saddle portions being spaced apart, and clamping means located between said spaced portions and engaging against said members for simultaneously holding the same against separation and clamping the conductor.
9. A suspension clamp of the character described comprising a pair of opposed members having spaced grooved portions adapted to engage beneath and support a conductor, and means located between said spaced portions in clamping engagement with the conductor and with said members for preventing separation of the latter.
- In testimony whereof I affix my signature.
- KARL KROLZIG.
